US00D990173S

(12) **United States Design Patent** (10) Patent No.: **US D990,173 S**
Masuyama et al. (45) Date of Patent: ** Jun. 27, 2023

(54) **FOAM SHEET**

(71) Applicant: **SEKISUI CHEMICAL CO., LTD.**,
Osaka (JP)

(72) Inventors: **Yoshikazu Masuyama**, Osaka (JP);
Katsunori Takahashi, Koka (JP);
Takanori Hamada, Koka (JP);
Kinryou Chou, Koka (JP)

(73) Assignee: **SEKISUI CHEMICAL CO., LTD.**,
Osaka (JP)

(**) Term: **15 Years**

(21) Appl. No.: **35/514,081**

(22) Filed: **Oct. 22, 2021**

(80) **Hague Agreement Data**

Int. Filing Date: **Oct. 22, 2021**

Int. Reg. No.: **DM/217465**

Int. Reg. Date: **Oct. 22, 2021**

Int. Reg. Pub. Date: **Apr. 22, 2022**

(30) **Foreign Application Priority Data**

Apr. 28, 2021 (JP) 2021-009158

(51) LOC (14) Cl. **05-06**

(52) U.S. Cl.

USPC **D5/47; D5/99**

(58) **Field of Classification Search**

(57) **CLAIM**

The ornamental design for a foam sheet, as shown and described.

DESCRIPTION

1. Foam sheet

1.1 : Front

1.2 : Back

1.3 : Top

1.4 : Bottom

1.5 : Right

1.6 : Left

(Continued)

The intended use of the foam sheet includes shock mitigation for automobiles, aircrafts, vessels and architecture.

1 Claim, 6 Drawing Sheets
